UNITED STATES PATENT OFFICE.

CHILTON E. BYINGTON, OF CHATTANOOGA, TENNESSEE.

GOLF TEE.

Application filed October 4, 1926. Serial No. 139,463.

This invention relates to golf tees, and the primary object of the invention is to provide a device of the class specified of a portable type and having features which overcome 5 the disadvantages of similar devices heretofore commonly used, and to replace these former devices by a peg of suitable cast metal and a weighted anchorage, and connecting means of an elastic character which 10 in part encapsulates the head of the peg and provides a ball-receiving cup, all of the parts being of soft vulcanized rubber except the weight means or the anchor, the means for holding the anchor, the connecting means 15 and ball-holding element all being in one piece.

A further object of the invention is to provide a portable device of the character specified which may be readily folded or reduced 20 so that it may be inserted in the pocket of the coat of the user or in any other convenient place of storage and easily set up in operative position when it is desired to bring the same into service.

With the foregoing and other objects and advantages in view, the invention consists in the construction and arrangement of the several parts which will be more fully hereinafter described and claimed.

In the drawing:

Figure 1 is a perspective view of a golf tee embodying the features of the invention;

Fig. 2 is a similar view, showing the improved tee folded or reduced for insertion 35 in an enclosure;

Fig. 3 is a plan view of the tee; and

Fig. 4 is a longitudinal section on the line 4-4, Fig. 3, looking in the direction of the arrows.

The improved tee comprises a peg or pin 5 having a rounded or cylindrically shaped head 6 embedded and held within a cap or ball-holding member 7 formed with an upper concaved seat 8 to receive the ball 9, as 40 clearly shown in the drawing. The peg or pin 5 is formed of cast metal, and is of such length as to provide for a stable insertion thereof in the ground, the said peg or pin tapering from the head 6 thereof to a sharp

50 point, as shown. Extending from the base of the cup member 7 is a connecting member 10 which extends to the center of one end of a base member or anchor 11 having embedded therein a weight 12 which may be 55 formed of lead or other metal. The base member or anchor 11, the connecting mem-

ber 10 and the cup member 7 are of vulcanized soft rubber and of integral formation.

It will be seen that the head 6 of the peg or pin 5 is encapsulated in the cup member 60 7 and tapers from the center of the latter in a vertical direction so that it may be readily embedded in the ground and at the same time position the cup member for practical service as a tee or ball-holding means. The 65 under side of the base or anchor member 11, the connecting member 10 and the cup member 7 form a flat support so that the said under side of these parts may rest upon the ground or other surface on which the complete tee is disposed. It will be understood that the weight 12 and the head 6 of the peg or pin 5 are molded respectively in the base or anchor 11 and the lower portion of 70 the cup member 7, and the molded rubber is subsequently subjected to a vulcanizing treatment. However, the exact mode of constructing or forming the members 7, 10 and 11 of the improved tee is not essential, it only being necessary in accordance with the 75 features of the invention that all of the said parts be integrally formed and that during the formation thereof the weight 12 and head 6 of the peg or pin 5 be secured therein. In making the peg or pin 5 of metal, 80 it is rendered more durable and may be more easily caused to penetrate or become embedded in the ground surface to positively hold the cup member 7, forming the tee proper, in true position for receiving the 85 ball 9.

The manner of placing the improved golf tee in position for use and the function of the base or anchor member 11 will be readily understood and the advantage ensuing 90 from the integral construction is that the improved device may be readily set up or applied for service at any point desired or found necessary and all the parts of the device will remain intact and will be generally serviceable for another period as compared to devices embodying parts which are 95 easily destructible or subject to rapid deterioration. The base or anchor member 11 with its weight 12 also serves to hold the 100 remaining parts of the improved tee in proper position and in the event that the cup member 7 and the peg or pin 5 become displaced, the said base or anchor member 105 will serve as a restricting means to irregular 110 movement to any material extent from the position of application of the tee prior to

the displacement thereof. The weighted base or anchor member also serves to hold the parts of the improved tee in proper position owing to its flat construction and greater extent both longitudinally and transversely of the remaining parts of the device and at the same time the connecting member 10 will have a yielding movement as will also the cup member 7 forming the tee proper.

As shown by Fig. 2, the improved tee is foldable or may be reduced in form, such reduction being permitted by the flexibility of the connecting member 10, and to accommodate this reduction and retention of the tee in folded condition, the weight 12 has an opening 12^a in the center thereof through which the peg or pin 5 is inserted with a sufficient degree of frictional tightness to retain the improved device in its reduced form so that it may be carried in the pocket of the coat of the user or placed within any other enclosure. To cover and shield the point of the pin 5 projecting through the opening 12^a when the device is folded as just specified, a cap 12^b is secured to or formed with the weight 12 over the said opening 12^a. Furthermore, the weight 12 may have the name of the owner and other identification matter applied thereto in any suitable manner.

What is claimed as new is:—

1. A golf tee comprising a tee member proper, a connecting member and a base anchor member all constructed integral and of yielding rubber, the tee member proper having a pointed peg with a curved head embedded therein, the peg depending from the said tee proper, and the base anchor member having a metal weight device secured therein and provided with a receptive opening with an enclosing shield means on one side for the point of the peg when the latter and connecting member are folded back to collapse the tee.
2. A golf tee of the class specified, comprising a cup member with an upper concavity forming the tee proper, a connecting member, a base anchor member having a weight enclosed therein with an opening

therethrough having an enclosing and shielding cap thereover, the cup member, connecting member and base anchor member being of integral construction and formed of rubber, the connecting member being united with the base anchor member at one end and continuing into the lower portion of the cup member, the lower sides of all the members being coincident and providing a flat surface, and a metallic peg having a reduced end and a rounded head embedded in the lower portion of the cup member, the reduced end being inserted in the said opening and enclosed by the cap when the tee is folded.

3. A golf tee of the class specified comprising a cup member, a connecting member and a base anchor member all integrally formed of rubber, the base anchor member having a metallic weight embedded therein at the edge portions with openings above and below the same and a shielded opening therethrough, the cup member having an upper concavity to provide a seat for a ball, and a peg having a rounded head embedded in the lower portion of the cup member, the peg depending vertically from the cup member and having a reduced end which is inserted in said opening and covered when the tee is folded.

4. A golf tee comprising a tee member proper, a connecting member and a base anchor member, all constructed integral and of yielding rubber, the anchor member having a metallic weight held therein and provided with an opening therethrough with a shield cap thereover, the tee member proper having a pointed peg with a head imbedded therein, the peg normally depending from the said tee proper and the connecting member being foldable to permit the pointed peg to be inserted through the opening of the metal weight, the connecting member being foldable for insertion of the pointed peg through the opening in the metal weight to hold the tee in reduced form.

In testimony whereof I have hereunto set my hand.

CHILTON E. BYINGTON.
